COMBINED PRESS AND CLAMP

Thomas H. Birch, Milwaukee, Wis.

Application October 24, 1950, Serial No. 191,903

1 Claim. (Cl. 303—1)

1

AB valves used with freight car brake equipment include a back cover on the service portion made in a die casting and therefore from white metal. The cover is secured to the cast iron valve body by two stud bolts and three cap screws passing through raised bosses spaced along the relatively thin margin of the back cover. In extremely cold weather, the differential contraction of the cover and the body causes the cover to buckle between the fastening devices enough to permit considerable leakage between the cover and the cast iron body of the AB valve. This is in effect brake pipe leakage, and has reached such proportions as to make it necessary to reduce the length of the trains in order to keep the air pressure in the system within legal limits. For instance, trains of 150 cars have been reduced to as little as 50 cars in extreme weather solely on account of this leakage.

The manufacturers have sought to correct the defect by providing improved back covers which apparently take care of the situation for new equipment, but that leaves some two million freight cars with the condition described. The situation is so serious that the Association of American Railroads has issued instructions that each time an AB valve with the old style back cover is dismantled for cleaning, the cover must be straightened in a suitably designed press. That, however, is an unsatisfactory expedient, even though the presses were provided at all the appropriate repair stations, for as soon as the car with the straightened cover goes into the extreme cold weather the distortion is repeated and the leakage renewed.

Replacing the covers on some two million cars with improved covers at a cost on the order of \$6.00 each presents a costly problem for the railroads.

The principal object of this invention is to provide a device that can be applied to the old style covers and will straighten them in place and hold them in proper position during service. Generally speaking, this is accomplished by means of a frame fitting over the marginal portion of the cover and the bosses and pressing against the marginal portions of the plate between the bosses so as to force those portions into appropriate pressure contact with the gasket and hold them there during service. The frame in effect bridges the space between the bosses, which are of different heights, and serves at once as a press to straighten a distorted cover and a clamp to hold it in proper position.

Fig. 1 is a front elevation of the back cover on the service portion of the AB valves;

2

Fig. 2 is an elevation of the opposite side or inside of the back cover;

Fig. 3 is a perspective view of the back cover and a brace device embodying this invention;

5 Fig. 4 is a section on the line 4—4 of Fig. 3;

Fig. 5 is an end elevation of the service portion of the AB valve with the brace device in position;

10 Fig. 6 is a front elevation of the brace device; and

Fig. 7 is a rear elevation of the same.

The back cover, generally indicated by 10, has a cylindrical dome 11 for the service piston return spring and associated parts and a cylindrical projection 12 for the release insuring valve. They are connected by a web 13. Extending from the projection 12 upwardly and outwardly past the dome 11 is a rib 14 in which there is a passage connecting auxiliary reservoir pressure with the 15 release insuring valve.

Extending outwardly and around the parts 11, 12, 13 and 14 is a generally flat marginal portion 15 provided with tubular bosses 16 and 17 for stud bolts 18 and 19 and tubular bosses 20, 21, and 25 22 for cap screws 23. The boss 16 is higher or projects further than the other bosses.

It is this marginal portion 15 between the spaced bosses that becomes distorted or buckled outwardly so as to permit the leakage referred to. Perhaps the distortion is due to greater contraction of the cast iron valve body, thus bringing the bolts and cap screws close together.

On the inside of the back cover, as shown in Fig. 2, there is what amounts to an inwardly directed flange 9 of varying width, surrounding the edge portion of the back cover and having its face on one level or one plane for cooperation with the corresponding face of the cast iron valve body with a sealing gasket between.

40 The brace device of this invention, indicated generally 24, is an open frame comprising a left side 25, a right side 26, a lower end 27, and an upper end 28 having openings 29, 30, and 31 aligned with the bosses 20, 21, and 22 and openings 32 and 33 aligned with the bosses 16 and 17.

The areas around the openings in the frame are in position to rest against the bosses on the back cover and be clamped to them by the bolts and cap screws. Between the openings 31 and 32, the side 26 is raised or offset outwardly at 35 to accommodate the greater height of the boss 16. This offset portion extends beyond the opening 32 to 36 to accommodate the extreme end of the rib 14. At 36, the frame is lowered or inset and extends around to the area surrounding the opening 29.

All along the outer margin of the frame 24 is an inwardly directed rib or flange 37 for contact with the corresponding portion of the back cover to force it into proper position and hold it there. In the form here shown, intended to be pressed from sheet metal, that rib is continuous, although the portions outwardly from the bosses on the back cover would not contact with the cover to any considerable extent. They might be omitted.

As shown by the section in Fig. 4, the lower end 27 is provided with an upwardly directed rib 38 and the left side 25 is provided with similar ribs 39, all of which add to the stiffness and strength of the end and side. The offsets 35 and 36 serve to give additional strength and stiffness to the right side and the upper end.

In order to apply the brace frame, the nuts are removed from the stud bolts 18 and 19 and the cap screws 23 are taken out. The stud bolts 18 and 19 are then removed and washers inserted in the bottom of the holes of a thickness corresponding to the thickness of the frame. The stud bolts are then replaced, the back cover is put on, and the frame 24 slipped over the stud bolts 18 and 19. The nuts are replaced on those stud bolts and the cap screws are inserted and screwed up, care being taken to tighten the screw threaded fastenings evenly.

If there is any distortion in the marginal portion of the back cover, the flange 37 will straighten it and force that marginal portion into proper contact with the gasket and hold it there.

The brace frame can be made in a variety of ways and will take form accordingly. The gist of the requirement is that it presents stiff beams in contact with the marginal portion of the back

cover between the bosses in order to force those portions into proper position and hold them there. Its shape must accommodate the difference in height between the boss 16 and the others and the projecting end of the rib 14.

I claim:

A combined press and clamp frame for straightening and maintaining straight the back cover of an AB valve which has buckled into leaking relation with the body of the valve and which includes an upstanding dome in its central area and bosses in its marginal area for receiving elements fastening the cover to the body, said frame comprising a rigid metallic plate having a central opening for passing said dome and having a marginal area internally contoured to accommodate said bosses and apertured to pass said fastening elements and provided with downwardly directed flanges between said boss-accommodating contours for pressing the marginal area of the cover firmly against the valve body when the frame is interposed between the body and cover and the fastening elements are set up.
